UNITED STATES PATENT OFFICE.

DWIGHT J. BLISS AND EDWARD J. RICHMOND, OF CARTHAGE, MISSOURI.

WATER-FILTER.

SPECIFICATION forming part of Letters Patent No. 611,426, dated September 27, 1898.

Application filed November 12, 1897. Serial No. 658,309. (No model.)

To all whom it may concern:

Be it known that we, DWIGHT J. BLISS and EDWARD J. RICHMOND, citizens of the United States, residing at Carthage, in the county of Jasper and State of Missouri, have invented certain new and useful Improvements in Water-Filters; and we do declare the following to be a full, clear, and exact description of the invention, such as will enable others skilled in the art to which it appertains to make and use the same.

Our invention relates to a novel form of filter, and the object is to provide a simple, inexpensive, and effective filter for general use that shall be automatically cleaned each time a quantity of water is drawn from the filter.

To these ends the invention consists in the construction, combination, and arrangement of the several parts of the device, as will be hereinafter more fully described, and particularly pointed out in the claims.

The accompanying drawings show our invention in the best form now known to us; but many changes in the details might be made within the skill of a good mechanic without departing from the spirit of our invention as set forth in the claims at the end of this specification.

In the accompanying drawings the same reference characters indicate the same parts.

Figure 1 is a perspective view of our improved filter. Fig. 2 is a front elevation with a portion of the casing removed to show the cleaning device. Fig. 3 is a vertical section. Fig. 4 is a horizontal section on the line 4-4 of Fig. 3. Fig. 5 is a similar view on the line 5-5. Fig. 6 is a vertical section through the valve-casing, taken at a right angle to that shown in Fig. 3. Fig. 7 is a detail view of the plug cock or valve removed from the casing. Fig. 8 is a detail view of the spring-pawl.

1 represents the cylinder or casing, and it may be of any size or dimensions to correspond to the capacity required. Its closed top is formed with a central externally-threaded stuffing-box 2 to receive the packing-gland 3, and its lower edge is provided with an annular flange 4, by means of which it is secured to the hollow base 5 by the bolts 6-6.

7 represents a central tubular shaft, its upper end extending through the stuffing-box 2,

and on this projecting end is fulcrumed the crank-handle 8 by means of the bolt 9, so as to permit a limited vertical movement of the outer end of said handle. The lower end of the tubular shaft 7 terminates in a taper plug-cock 10, which has a bearing in the valve-casing 12, which may be formed integral with the base 5. This casing 12 is provided with an inlet-pipe 13 and an outlet-pipe 14, which terminate in a gooseneck 15 for the discharge of the filtered water.

16 represents a radial passage in the plug-cock, which is aligned with the inlet-pipe 13, and it communicates with the vertical passage 17 in the tubular shaft 7, and the upper end of the passage 17 terminates in a series of radial orifices 18-18.

19 represents an annular disk resting upon the annular shoulder 20 of the plug-cock, and 21 represents a packing ring or gasket to form a joint between the disk 19 and the lower end of the filtering-cylinder 22. A similar gasket 23 is located between the upper end of said cylinder 22 and the disk 24, which is clamped to the upper end of the cylinder by the nut 25, engaging the threaded portion 26 of the shaft 7.

27 represents a hood or bonnet which encompasses the upper end of the shaft above the porous cylinder, and it serves to deflect the water from the orifices 18 and distribute it evenly over the outside surface of the cylinder.

28 represents a radial passage in the plug-cock, which is aligned with the outlet-pipe 14, and it connects with a vertical passage 29, which in turn communicates with the interior of the porous cylinder.

30 represents an air-chamber depending from the disk 24, so as to occupy the space in the upper end of the filtering-cylinder.

31 represents a curved plate fixed on the upper end of the outside of the casing 1, and it is provided with two stop-notches 32 and 33, located in the path of the outer end of the lever-handle 8.

34 represents a spring-pawl fixed on the upper face of the base 5, and its free end is adapted to engage a notch or recess 35, formed in a flange 36, depending from and extending part way around the lower disk 19, so as to permit the porous cylinder to be rotated in

one direction and prevent it being rotated in the opposite direction.

37 represents the waste-pipe, the upper end of which terminates in a valve-seat 38, located 5 in the base 5, and 39 represents a valve pivoted on one end of a lever 40, fulcrumed in the bracket 41, fixed to the base. The opposite end of the lever 40 projects upwardly and into the path of the depending flange 36, so that 10 in rotating the porous cylinder the flange 36 presses the free end of the lever 40 down, thereby raising the valve and permitting the water in the casing to escape.

41' represents a vertical shoe secured to the 15 ends of two parallel springs 42 42, fixed at their opposite ends to the inside wall of the casing, and 43 represents a strip or bar of sandstone or similar abrading material held in the shoe and arranged to be held in contact with the outer face of the porous cylinder. A scraper-blade 44 is pivoted to the shoe 41, and its edge is held in contact with the cylinder by means of the spring 45.

The operation of the filter is as follows:

25 When the lever 8 rests in the notch 32 in the plate 31, the feed-water is on and passes up through the tubular shaft 7, out through the orifices 18, and under the hood 27, which deflects it over the outside of the porous cylinder, through which it passes, and compresses the air in the air-chamber 30, and if the lever 8 is now raised from the notch 32 and turned to the right the feed-water is turned off, and the water inside of the porous cylinder is 30 forced outwardly through the walls of the porous cylinder, and at the same time the sandstone bar 43 and the blade 44 remove the slime or sediment from the outside of the porous cylinder, and the flange 36 raises the sediment-valve 39 to allow the escape of the refuse. The lever-handle may now be turned around and left to rest in the notch 33, in which position both the inlet and the discharge pipe are open and a continuous flow 45 of filtered water is discharged at the goose-

neck-outlet. When sufficient filtered water has been discharged at the outlet-pipe, the lever is moved forward to the notch 32, which cuts off the discharge, but leaves the inlet on. Consequently the filtered water accumulates 50 in the porous cylinder until the air-pressure in the air-chamber counterbalances the water-pressure in the inlet-pipe.

Having thus fully described our invention, what we claim as new and useful, and desire to 55 secure by Letters Patent of the United States, is—

1. A filter comprising the cylinder 1, provided with the valve-casing 12 having the water inlet and outlet in combination with 60 the central tubular shaft 7, provided with the radial orifices 18, and the plug-cock 10 having corresponding inlet and outlet passages, the concentric porous cylinder 22 and the air-chamber 30, and means, substantially as set 65 forth, for simultaneously operating said plug-cock and porous cylinder, as and for the purpose set forth.

2. A filter comprising the cylinder 1, provided with the valve-casing 12 formed with 70 the inlet 13 and the outlet 14, the retaining-spring 34, and the notched plate 31, in combination with the spring-actuated scraper 44 and abrading bar 43; the vertical tubular shaft 7 provided with the orifices 18, the plug-cock 10 fixed to the lower end of said shaft, the flanged disk 19 and the hand-lever 8, pivotally secured to said shaft and adapted to 75 engage the notched plate, the porous cylinder 22 and the connected air-chamber 30 removably secured to said shaft, concentric with the cylinder 1, substantially as described.

In testimony whereof we hereunto affix our signatures in presence of two witnesses.

DWIGHT J. BLISS.
EDWARD J. RICHMOND.
